UNITED STATES PATENT OFFICE

BELA DE NAGY, OF NEW YORK, N. Y., ASSIGNOR OF THIRTY-EIGHT AND ONE-FOURTH PER CENT TO NICHOLAS M. MOLNAR, OF NEW YORK, N. Y., AND TWENTY-TWO AND ONE-HALF PER CENT TO NICHOLAS BRUCKNER, OF ASTORIA, LONG ISLAND, NEW YORK

DESIGN FOR A BRUSHING AND POLISHING MACHINE

Application filed May 12, 1933. Serial No. 48,082. Term of patent 3½ years.

To all whom it may concern:

Be it known that I, BELA DE NAGY, a citizen of the United States, residing at #336 W. 89th Street, New York, in the county of New York and State of New York, have invented a new, original, and ornamental Design for a Brushing and Polishing Machine, of which the following is a specification, reference being had to the accompanying drawing, forming part thereof,

Fig. 1 is a plan view of a brushing and polishing machine.

Fig. 2 is a side elevation thereof.

I claim:

The ornamental design for a brushing and polishing machine, as shown.

BELA DE NAGY.
